UNITED STATES PATENT OFFICE.

CHARLES W. GIBBS, OF BRIDGEPORT, CONNECTICUT.

LOCK-NUT.

SPECIFICATION forming part of Letters Patent No. 783,630, dated February 28, 1905.

Application filed August 22, 1904. Serial No. 221,747.

To all whom it may concern:

Be it known that I, CHARLES W. GIBBS, a citizen of the United States, residing at Bridgeport, in the county of Fairfield and State of Connecticut, have invented a certain new and useful Improvement in Lock-Nuts, of which the following is a specification, and the accompanying drawings show the construction of the new and improved lock-nut and the proper way to use it.

I am aware that there are many patent lock-nuts; but my object in the invention has been to so construct a nut that it shall be of greater use to the public, and my experience as a manufacturer of nuts has shown that such a nut must have the following features, all of which are incorporated in my new invention called the "Paragon" lock-nut: First, the nut has a double grip, thus making certain that the nut will not shake loose; second, it has a draw-bolt strain equal to a common nut; third, it can be used either end against the work, thus being a safeguard against accident should a nut be placed on a bolt wrong; and 25 it can also be locked on a bolt or rod at any place desired without either end of the nut being against any object; fourth, it is as strong as a common nut, having the same appearance when locked, and is made standard 30 in dimensions; fifth, its locking device is under full control of the operator, who can lock or unlock the nut in an instant just when and where he pleases without the use of any tools other than the wrench in common use on nuts; 35 sixth, having designed tools and method whereby the new nut can be easily made it thus becomes possible to bring it into general use, thus being of great value to the public. In order to construct such a nut, I have found 40 it necessary to make it in two parts or sections.

Figure 1 shows in side elevation the two parts or members of the improved lock-nut mounted on a bolt and separated from each other. Fig. 2 represents a similar view, partially in section, of the nut with its two members in the locked position. Fig. 3 is a perspective view showing the arrangement of the slots and depth of the same, their number,

depth, and location in the conical extension 50 of the base being of great importance.

I am aware that the number and width of the slots may be changed without departing from the spirit of the invention, so long as the slots do not extend in depth entirely 55 through the wall of said base and conical extension; but the three slots, their location, and depth are of great value in the invention as a locking device.

In Fig. 1, A represents a common three-by- 60 five-eighths bolt. B represents that member of the nut known as the "base" or part designed to be placed against the work. This base is made with either a square or hexagon shaped exterior, as may be desired, and stand- 65 ard in size to fit the wrench used in screwing the nut to position. This base B has a conical-shaped projection c, which is divided into three equal parts by three slots F F F, each slot extending through one wall of the cone c 70 in a direction at right angles to the bore of the member and downward through the cone c and into the base B to a depth equal to about two-thirds the entire height of said member. The bottom of the base B is slightly concave 75 in shape, as indicated by the dotted line D, which is exaggerated in order to plainly show the idea. It is the peculiar construction of this member which makes this lock-nut of great value. The member E is the top of the 80 nut and, like the base, has an exterior of standard shape and size. This member has a bore the same size as the bore in the base, both members being tapped to fit the bolt on which they are to be used. This top member E has 85 in one end a conical-shaped socket H, proportioned to the size and shape of nut desired, and each nut to fit over the corresponding conical projection in member B.

To use the nut, place the member B on the 90 bolt with the concave bottom facing the parts which are to be held. Then put on the top E, with the conical socket facing the conical projection of the member B, and screw it up until the two parts meet. Then place the 95 wrench on the nut, covering both members and screw up just as you would a common nut until the work is drawn tightly together,

and then slipping the wrench off the member B onto the member E turn this member up until the nut is firmly locked. To remove the nut, place the wrench on the member E, give it a turn off, and then, slipping the wrench over both members, remove as you would a common nut.

The base B is of peculiar construction and works as follows: In screwing the member B against a piece of work the concave bottom acts as a lever and throws the three parts of the conical extension C (which are made by the three slots F F F) in against the threads of the bolt and gives us a good lock. Now when the member E is screwed up against the member B, the conical socket H fitting over the conical extension c, the three parts of the cone c are held firmly in place, and the nut is locked still more firmly by the thrust of the socket H against the cone c and the similar

action between the threads of the bore of the top member E and the threads of the bolt, and there we have a double lock-nut of great strength and gripping power and having an appearance when locked like a common nut. 25

Having thus described my invention, I claim as new and desire to secure by Letters Patent—

The combination of the member E having the conical socket H, with the base or member B, furnished with the concave bottom D, 30 and the conical extension C furnished with the slots F, all being as and for the purpose described.

In testimony whereof I affix my signature in the presence of two witnesses.

CHAS. W. GIBBS.
